UNITED STATES PATENT OFFICE.

MAX STOCKOV, OF NEW YORK, N. Y.

APPAREL-HANGER-SUPPORTING BRACKET FOR WARDROBE-TRUNKS.

1,285,455.

Specification of Letters Patent. Patented Nov. 19, 1918.

Application filed June 10, 1918. Serial No. 239,330.

To all whom it may concern:

Be it known that I, MAX STOCKOV, a subject of Russia, residing in the borough of Manhattan, in the city, county, and State of New York, have invented new and useful Improvements in Apparel-Hanger-Supporting Brackets for Wardrobe-Trunks, of which the following is a specification.

This invention relates to supporting brackets for apparel hangers particularly adapted for use in wardrobe trunks, and it is the object of the invention to provide an improved hanger supporting bracket of this character which is readily adjustable to form a compact structure to be inclosed in the trunk and being adjustable to be withdrawn from the trunk to extend out from the trunk and support the hangers with apparel in such position to facilitate the placing of apparel on the hangers and into the trunk and remove them therefrom, and to provide a hanger support which is novel, simple and cheap in construction and efficient in use.

In the drawing accompanying and forming a part of this specification, Figure 1 is a front elevation of a wardrobe trunk, partly open and one section of the trunk in section, with my improved hanger support applied thereto showing in full lines the position of the support when the trunk is to be closed, and in dotted lines in adjusted position to facilitate the placing of apparel hangers thereon and remove the same.

Fig. 2 is a longitudinal sectional view of the hanger support adjusted to position to be withdrawn from the trunk; and

Fig. 3 is an enlarged cross sectional view taken on the lines 3—3 of Fig. 1 looking in the direction of the arrows.

Similar characters of reference designate like parts throughout the different views of the drawing.

In the drawing I have shown my invention applied to a wardrobe trunk consisting as usual of a pair of hingedly connected sections 4 and 5, the section 5 being provided with a series of drawers 6 and the section 4 being arranged to contain apparel carried by hangers supported by brackets carried in said section of the trunk.

I have shown an embodiment of my invention in connection with a trunk of this character, comprising a rod 10 having a plate or bracket 11 secured at the end and an angle bracket 12 to which the rod is secured

adjacent the opposite end and by means of which brackets 11 and 12 the rod is secured in fixed position to the back and side walls of the trunk section 4. In practice there are two of the hanger supporting brackets provided, one adjacent each side wall of the trunk section 4, but for the purpose of convenience of illustration and describing the invention only one of the brackets is shown. 65

The hanger support comprises a pair of movably connected sections or bars 14 and 15 whereby the sections may be adjusted to extend at an angle to each other to permit of the inclosing of the same in the trunk when closed, and adjusted to extend in a direction to form a continuation of each other to facilitate the placing and removal of hangers carrying apparel supported upon the support. 75

The bar 14 of the support is in the form of a channel bar bent up from sheet metal to substantially U-shape in cross section, as shown in Fig. 3. This bar is mounted upon the rod 10 with the open side of the channel bar downward whereby the bar is adapted to have longitudinal sliding movement on the rod, the walls of the channel bar being connected by pins 16 and which also serve as stops to engage with the bracket 12 to limit 80 the outward movement of the channel bar. 85

Secured within the channel portion of the bar 14 at the forward end to extend beyond said end of the bar and laterally or downward thereof is an arm or ear 17, which may consist of a pair of connected and spaced plates, or may be a single piece of metal bent upon itself for a purpose to be hereinafter described. The section or member 15 is also of channel shape bent up from sheet metal 90 the same as the bar 14, and is arranged to straddle the extension 17 at its inner end and pivotally connected thereto, as at 18, whereby said member 15 is adapted to have movement on its pivot support to move said 100 bar to the position shown in full lines in Fig. 1 to permit of the closing of the trunk sections, or to move said bar to the position shown in dotted lines in Fig. 1, or the position shown in Fig. 2, to form or constitute 105 a continuation of the supporting bar section 14.

To rigidly support and releasably retain the supporting section or bar 15 in the position shown in Fig. 2 to form a continuation of the bar 14 there is provided a latch 110 20 pivotally supported at one end to one

side of the pivotal connection of the bar sections 14 and 15, as at 21 by the extension 17, said latch being arranged to have a part to engage in the channel portion of the bar 5 15 and having a notch or recess 22 to engage a pin 23 extending transversely of said bar. The free end of the latch is formed with a finger piece 24 to project from the channel portion of the bar whereby to manipulate the latch to free it from the pin 23 to permit of the moving of the channel bar member 15 to the position shown in full lines in Fig. 1.

The normal position of the support with 15 the trunk sections in closed position is as shown in Fig. 1 with the channel bar section 15 of the support extending at an angle to and downward from the channel bar 14. As the trunk is opened to remove the hangers with the apparel, the channel bar 15 is raised to the position shown in Fig. 2, this upward movement being limited by the end of said bar section abutting against the end of the bar section 14. During the upward 20 movement of the bar section 15 the latch 20 is moved upward therewith by the engagement thereof with the pin 22, and as the bar 15 reaches the limit of its upward movement the latch notch 22 will engage the pin 23 whereby the latch not only serves as a supporting bracket for said channel bar section 15 but also to retain or lock it in such position. In this position the hanger sections 14 and 15 may be pulled outward to 25 the position shown in dotted lines in Fig. 1 together with any hangers thereon by the section 14 moving along the rod 10, any weight on said bars, such as hangers with apparel, being taken up by the pins 16 engaging with the rod. To cause the hangers on the channel bar sections 14, 15 to move with said bars the bar section 14 has an upwardly turned flange 26 to serve as a stop for the hangers, and the outer end 30 of the bar 15 also has an upwardly extending flange 27 at the outer end in the form of a disk carried by a stud secured in the channel portion of the bar. To adjust the supporting bracket to close the trunk the 35 bars 14, 15 are moved from the dotted line position in Fig. 1 to the position shown in Fig. 2, when the latch notch 22 is thrown out of engagement with the pin 23 by lifting the latch by the finger piece 24, when 40 the bar section 15 may be moved to the full line position shown in Fig. 1 and in position to permit of the closing of the trunk.

Having thus described my invention, I claim:

60 1. A hanger support for wardrobe trunks, comprising a rod arranged to be supported

in fixed position; a pair of pivotally connected members, one of which members is mounted upon the rod to have longitudinal movement and the other member adapted to extend in a direction to form a continuation of the first member and at an angle thereto; and a latch pivotally carried at one end by the first member at one side of the pivotal connection of the members and arranged to coöperate with the other member to rigidly support it in position to form a continuation of its companion member and releasably retain it in such position.

2. A hanger support for wardrobe trunks, 75 comprising a rod supported in fixed position; a pair of pivotally connected bars of inverted U-shape in cross section mounted upon the rod to have longitudinal movement and arranged to extend at an angle 80 to each other and form a continuation one of the other; and a latch pivotally carried by one of said bars and coöperate with the other bar to releasably retain the bars in position to form a continuation one of the 85 other for the purpose specified.

3. A hanger support for wardrobe trunks, comprising a rod supported in fixed position; a channel bar mounted on the rod to have a limited longitudinal movement; a 90 channel bar pivotally connected to the end of the first channel bar and arranged to extend at an angle to or form a continuation of the first channel bar; a latch pivotally connected at one end to a lateral extension 95 of the first channel bar and the free end arranged to coöperate with a transverse pin carried by the second channel bar to releasably retain said bar in position to form a continuation of the first bar for the purpose specified.

4. A hanger support for wardrobe trunks, comprising a rod supported in fixed position; a channel bar mounted on the rod to have a limited longitudinal movement and 105 having a lateral extension at one end; a channel bar movably connected to said lateral extension of the first bar to extend at an angle to and in a direction to form a continuation of the first bar; a latch pivotally supported at one end by the lateral extension of the one channel bar and the free end arranged to engage in the channel portion of the movable bar and having a notch to engage a pin extending transversely 110 of said bar by gravity as said bar is moved to position to form a continuation of the first bar to releasably support said bar in such position; and upwardly extending flanges at the outer ends of the channel bars 115 120 for the purpose specified.

MAX STOCKOV.
